ELECTRIC BREAD TOASTER SWITCH

Henry L. Olson and Robert A. Miller, Grand Haven, Mich., assignors to Camfield Manufacturing Company, Grand Haven, Mich., a corporation of Michigan

Original application February 4, 1950, Serial No. 142,366, now Patent No. 2,622,505, dated December 23, 1952. 10 Divided and this application June 10, 1950, Serial No. 167,418

8 Claims. (Cl. 200—67)

The herein disclosed invention relates to electric bread toasters and has for an object to provide a bread toaster in which a switch mechanism is used by means of which the switch contacts are positively held closed.

An object of the invention resides in providing a construction utilizing a switch lever having a contact carrying arm and an actuating arm and in addition thereto an energizing arm with a spring acting between said arms to give to the switch lever snap action upon opening and closing of the switch.

An object of the invention resides in providing a construction in which greater force is exerted by the spring to hold the switch closed than opened.

Another object of the invention resides in arranging the axes of the pivots for said switch lever and energizing arm in spaced parallel relation and in making the energizing arm longer than the actuating arm to cause the ends of the spring to travel along arcs of circles gradually approaching one another whereby greater pressure will be exerted by the spring to hold the switch in closed position than in open position.

Other objects of the invention reside in the novel combination and arrangement of parts and in the details of construction hereinafter illustrated and/or described.

In the drawings:

Fig. 1 is an elevational sectional view of a toaster illustrating an embodiment of the invention.

Fig. 2 is a cross sectional view taken on line 2—2 of Fig. 1.

Fig. 3 is a view similar to Fig. 2 showing the parts in altered position.

This application is a division of the copending application for patent of Henry L. Olson and Henry J. Freeze, Serial No. 142,366, filed February 4, 1950, now Patent No. 2,622,505, issued December 23, 1952.

For the purpose of illustrating the invention a portion of an electric bread toaster has been shown and which consists of the usual toasting mechanism confined within a case A. Within this case is a frame B which includes an end frame member 33 and on which the switch mechanism G of the invention is mounted. The toasting mechanism is operated by a lever 88 pivoted to frame B. The switch mechanism includes a switch lever pivoted for movement relative to the frame in an up and down direction and having a contact carrying arm and an actuating arm. On the contact carrying arm is provided movable contacts adapted to contact fixed contacts carried by the frame. An energizing arm is pivoted for movement relative to the frame about an axis parallel to the axis of the pivot for the switch lever. The energizing arm has an end projecting outwardly beyond the end of the short arm and which has a greater extent of travel than the end of the actuating arm. At the ends of said arms are provided spring engaging members and between the same is an overcenter spring which causes snap action of the switch lever when the energizing arm is moved. A link is connected to the operating lever of the toaster and is also connected through a lost motion connection with said energizing arm. These various parts will now be described in detail.

The switch mechanism G of the invention is best shown in Figs. 1 and 2. This switch mechanism includes a support 199 which is stamped from sheet metal and which has legs 200 projecting outwardly therefrom. These legs are attached to the end frame member 33 of the toaster and hold the support 199 spaced from

2

said end frame member. The lowermost part of this support 199 has flanges 201 projecting outwardly therefrom and which have attached to them a bar 202 of insulating material. Rivets 203 extend through these parts and hold the same attached. This bar of insulating material carries two fixed contacts 204 and 205 which are mounted on screws 206 and 207 which are secured to said bar. These contacts are connected in the circuit for the heating elements of the toaster in the usual manner. The contacts 204 and 205 lie in a substantially horizontal plane. Pivoted to the support 199 is a switch lever 208 constructed of insulating material. This lever is mounted on a stud 209 secured to the support 199 and which forms the pivot means therefor. A clip 210 attached to the end of this stud holds the said lever in position thereon. The lever 208 has a long arm 211 which has been referred to as a contact carrying arm and which has pivoted to it by means of a rivet 212 a swinging contact bar 213. This bar has ears 214 extending upwardly therefrom and through which the rivet 212 extends. The said contact bar is also formed with movable contacts 215 which when the lever 208 is swung in a clockwise direction engage the contacts 204 and 205 and closes the circuit through the same. The lever 208 has at its other end a short arm 216 which will be referred to as an actuating arm and which is formed with a slot 217. In this slot is received one end of a compression coil spring 218, the other end of which encircles a lug 219 formed on an arm 220. The end of arm 216 adjacent said slot and lug 219 will be referred to as spring engaging members. Arm 220 is formed at its end opposite the lug 219 with a U-shaped portion 221. A stud 222 extends through this portion and is attached to the support 199. By means of this construction the arm 220 is held from twisting even tho the lug 219 is offset from said arm. Disposed adjacent the arm 220 is a companion arm 223 which is attached at one end to the arm 220 by means of a rivet 224. This arm is straddled by the U-shaped portion 221 of arm 220 and the stud 222 passes through this arm as well as said U-shaped portion. The arm 223 hence travels in unison with the arm 220. The axis of the stud 222 is parallel to the axis of the stud 209; and both are on the same side of a plane containing the contacts 204 and 205; the stud 209 being closer to said plane than the stud 222. The distance between the lug 219 and the axis of the stud 222 is greater than the distance between the slot 217 and the axis of the stud 209. This causes the ends of the spring 218 to travel along the arcs of two circles indicated by the reference numerals 240 and 241. It will be noted that these arcs approach each other at their lower ends. This causes the spring 218 to be more compressed at the lower position thereof shown in Fig. 3 than in its upper position shown in Fig. 2. Consequently greater pressure is exerted to hold the switch closed than open. On the arm 223 is formed a finger 225 which extends outwardly therefrom and which is adapted to engage the upper surface of a stop 226. This finger limits upward movement of the end of the lever to which spring 218 is attached. The stop 226 is so situated that the upper surface of the switch lever 208 strikes the lower surface of this stop. In this manner the upward movement of the contact bar 213 is terminated. The stop 226 is struck out from the support 199 and is situated near the upper portion of the same.

The switch mechanism G is operated by the lever 88. This lever has formed in it a key hole 227. A link 228 is pivoted to said lever through this hole. For the purpose, the said link at its upper end has an offset 229 which is formed with a neck 230 and with a head 231 at its outer end. The head 231 is insertable into the slot 227 by holding said link horizontal and when turned to a vertical position the neck 230 becomes seated in the circular part of said slot and is pivotally attached to said lever. The lower end of the link has formed in it a slot 232. A stud 233 passes through this slot and is secured to the companion arm 223. This slot provides a lost motion connection between the toaster operating lever and switch mechanism whereby the toaster is not energized until said lever approaches its lowermost position.

The operation of the invention is as follows: The

parts are normally situated as illustrated in Fig. 2. When the lever 88 is depressed the timing mechanism of the toaster is energized. The link 228 travels downwardly with the lever 88 and when the stud 233 reaches the upper end of slot 232 arm 220 is depressed. This causes the spring engaging member 219 to travel in the arc of the circle indicated at 240. As the said spring engaging member passes a line connecting spring engaging member 217 and stud 222 the lever 208 is rotated in a clockwise direction and the contact bar 213 moves downwardly to bring the contacts 215 in engagement with the contacts 204 and 205. This energizes the heating elements of the toaster. It will be noted that the arc 240 through which the spring engaging member 219 passes and the arc 241 through which the spring engaging member 217 passes approach each other so that when the switch is in closing position the spring 218 is compressed to a greater extent as shown in Fig. 3 than when the switch is in open position as shown in Fig. 2. Upon opening of the switch the operation is exactly reversed.

The advantages of the invention are manifest. The switch is of the snap action type whereby rapid opening and closing of the switch is made possible to reduce arcing across the contacts. The switch is operated by the operating lever so that the number of intervening parts is a minimum. In this manner the operation of the switch becomes positive. The entire switch is mounted on a single support permitting of easy assembly of the parts before installation of the switch on the toaster framework. Movement of the contacts occurs in the same direction as the movement of the operating portion of the operating lever. Due to the lost motion connection between the operating lever and switch mechanism the switch is not actuated until the operating lever is near the end of its travel, thereby preventing energization in the event that the bread is not well within the bread oven. By the arrangement of the pivots for the moving parts of the switch and the lengths of the arms thereof greater compression of the switch actuating spring occurs when the switch is closed than when open. This causes increased pressure on the contacts when the switch is constructed as disclosed than would be possible with the conventional type of switch.

Changes in the specific form of the invention, as herein described, may be made within the scope of what is claimed without departing from the spirit of the invention.

Having described the invention, what is claimed as new and desired to be protected by Letters Patent is:

1. In combination a frame, an operating member guided for movement relative to said frame, a switch lever pivoted for movement relative to said frame and having an actuating arm and a contact carrying arm, a fixed contact carried by said frame, a movable contact carried by said contact carrying arm and adapted to make contact with said fixed contact, an energizing arm pivoted for movement relative to said frame about an axis parallel to the axis of the pivot of said switch lever, said energizing arm having an end projecting outwardly beyond the end of the actuating arm of said switch lever and having a greater extent of travel than the end of said actuating arm, an over-center spring acting between the ends of said arms, a stop fixed relative to said frame, a finger movable with said energizing arm and engageable with said stop to limit movement thereof, said switch lever having a part engageable with said stop to limit movement of said switch lever into switch opening position and a connection between said energizing arm and said operating member.

2. In combination a frame, an operating member guided for movement relative to said frame, a switch lever pivoted for movement relative to said frame and having an actuating arm and a contact carrying arm, fixed contact carried by said frame, a movable contact carried by said contact carrying arm and adapted to make contact with said fixed contact, an energizing arm pivoted for movement relative to said frame about an axis parallel to the axis of the pivot of said switch lever, said energizing arm having an end projecting outwardly beyond the end of the actuating arm of said switch lever and having a greater extent of travel than the end of said actuating arm, an over-center spring acting between the ends of said arms, a stop fixed relative to said frame, a finger movable with said energizing arm and engageable with said stop on one side thereof to limit movement thereof, said switch lever having a part engageable with said stop on the other

side thereof to limit movement of said switch lever into switch opening position and a connection between said energizing arm and said operating member.

3. In combination a frame, an operating member guided for movement relative to said frame, a switch lever pivoted for movement relative to said frame and having an actuating arm and a contact carrying arm, fixed contact carried by said frame, a movable contact carried by said contact carrying arm and adapted to make contact with said fixed contact, an energizing arm having a U-shaped end, a stud fixed relative to said frame and extending through said U-shaped end and restraining twisting of said arm, said energizing arm having an end projecting outwardly beyond the end of the actuating arm of said switch lever and having a greater extent of travel than the end of said actuating arm, a spring engaging member on the end of said energizing arm offset from said energizing arm, an overcenter spring acting between said spring engaging member and said end of said actuating arm and a connection between said energizing arm and said operating member.

4. In combination a frame, an operating member guided for movement relative to said frame, a switch lever having a contact carrying arm and an actuating arm, pivot means therefor having an axis fixed relative to said frame, a fixed contact carried by said frame and a movable contact carried by the contact carrying arm of said switch lever, an energizing arm, pivot means therefor having an axis fixed relative to said frame and parallel with and spaced from said first named axis, a spring engaging member on said actuating arm, a spring engaging member on said energizing arm, a spring acting between said spring engaging members, and adapted when the spring engaging member on the actuating arm is to one side of a line passing through the other spring engaging member and the axis of the switch lever to urge said lever to move the movable contact into switch closing position and when on the other side of said line to cause said movable contact to move into switch opening position, stops for limiting the movement of said switch arm to switch opening and switch closing positions, said spring engaging members traveling through eccentric arcs of different radii approaching one another when the switch arm is in closing position to cause the spring to exert a greater pressure on the switch arm when the contacts are in switch closing position than when in switch opening position and a connector between said operating member and said energizing arm.

5. In combination a frame, an operating member guided for movement relative to said frame, a switch lever having a contact carrying arm and an actuating arm, pivot means therefor having an axis fixed relative to said frame, a fixed contact carried by said frame and a movable contact carried by the contact carrying arm of said switch lever, an energizing arm, pivot means therefor having an axis fixed relative to said frame and parallel with and spaced from said first named axis, a spring engaging member on said actuating arm, a spring engaging member on said energizing arm, a spring acting between said spring engaging members and adapted when the spring engaging member on the actuating arm is to one side of a line passing through the other spring engaging member and the axis of the switch lever to urge said lever to move the movable contact into switch closing position and when on the other side of said line to cause said movable contact to move into switch opening position, stops for limiting the movement of said switch arm to switch opening and switch closing positions, the distance between the axis of the pivot for the actuating arm and the spring engaging member on said arm being greater than the distance between the axis of the pivot for the energizing arm and the spring engaging member on said arm to cause said spring engaging members to travel through eccentric arcs of different radii approaching one another when the switch arm is in closing position to cause the spring to exert a greater pressure on the switch arm when the contacts are in switch closing position than when in switch opening position and a connector between said operating member and said energizing arm.

6. In combination a frame, an operating member guided for movement relative to said frame, a switch lever having a contact carrying arm and an actuating arm, pivot means therefor having a horizontal axis fixed relative to said frame, a fixed contact carried by said frame and disposed

below said axis, and a movable contact carried by the contact carrying arm of said switch lever, an energizing arm, pivot means therefor having an axis fixed relative to said frame and parallel with and spaced from said first named axis, said second named axis being disposed above and at a locality between the contacts and said first named axis, a spring engaging member on said actuating arm, a spring engaging member on said energizing arm, a spring acting between said spring engaging members the distance between said first named spring engaging member and the axis of the pivot of said actuating arm being less than the distance between the second named spring engaging member and the axis of the pivot for said energizing arm, to cause said spring to exert a greater pressure on said contacts when the switch lever is in contact closing position than when in contact opening position and a connector between said operating member and said energizing arm.

7. In combination a frame, an operating member guided for movement relative to said frame, a switch lever having a contact carrying arm and an actuating arm, pivot means therefor having an axis fixed relative to said frame, fixed contacts carried by said frame and disposed in a plane parallel to the axis of said pivot means, movable contacts carried by said contact carrying arm and engageable with said fixed contacts, said pivot means being disposed to one side of said contacts, an energizing arm, pivot means therefor having an axis fixed relative to said plane and spaced from and parallel to the axis of said first named pivot means, said second named axis being disposed more remotely from said plane than said first named axis, spring engaging members on said actuating arm and on said energizing arm, a spring acting between said spring engaging members, the distance between the axis of the pivot means for the energizing arm and the spring engaging member thereon being greater than the distance be-

tween the axis of the pivot means for said switch lever and the spring engaging member thereon to cause said spring to exert a greater pressure on said contacts when the switch lever is in contact closing position than when in contact opening position and a connection between said operating member and said switch lever.

8. In combination, a support, a switch lever having a contact carrying arm and an actuating arm, pivot means therefor having an axis fixed relative to said support, a fixed contact carried by said support and a movable contact carried by said contact carrying arm of said switch lever, an energizing arm, pivot means therefor having an axis fixed relative to said support and parallel with and disposed in juxtaposition with the axis of said first named pivot means, a spring engaging member on said actuating arm, a spring engaging member on said energizing arm, a spring acting between said spring engaging members and when the parts are in one position urging the contacts apart and when in another position urging the contacts into engagement, the distance between the spring engaging members on the energizing and actuating arms being closer together when the contacts are in engagement than when apart to increase the spring pressure between the fixed contact and the movable contact when in engagement.
